ANTIWEAR PIECE FOR BAGS, BRIEF CASES, AND THE LIKE

Application filed February 22, 1929. Serial No. 341,859.

The present invention relates to the art of school bags, brief cases and similar articles and more especially to the inexpensive kind, meaning not made from genuine leather derived from various hides. This invention has further reference to an improved anti-wear piece especially adapted for use in connection with school bags, brief cases and the like of the very economical type, and where suitable metal reinforcing pieces are used in the over or cover flap, to withstand the strain on the flap incident to the weight strain of the bag on the handle.

In other words all school bags, brief cases and the like have a metal reinforcing strip, some exposed and some covered, on the inner face of the cover or over flap, the reinforcement being secured to the flap by riveted loops, which carry the handles, together with rivets at the end of the reinforcing strip. It usually occurs that the ends of this reinforcing strip eventually cut through the cover or over flap, in which case the flap quickly wears out.

In the expensive school bags, brief cases and the like, that is those made out of genuine leather from the hides, the metal reinforcing strip in the flap is usually covered the full length by a strip of genuine leather, and in the majority of such articles the covering for the reinforcing extends approximately the length of the handle, not substantially the full length of the flap, and due to such bags being made of genuine leather from the hide, there is no wearing through of the flap. The fact is such bags otherwise wear out and become useless.

In view of these facts the purpose of this invention is to provide an improved anti-wear piece between the ends of the reinforcing and the cover or over flap, to prevent the ends of the metal reinforcing from wearing through the flap, and in accomplishing this purpose it is the aim to distinguish the character of bag, brief case or the like of the economical kind from the more expensive type, such as those made of genuine leather from the hide.

A further purpose is to apply this anti-

wear piece particularly to school bags, brief cases and the like made of any extremely economical suitable material of a fabric or fibre kind, rubberized or otherwise made waterproof, or imitation leather preferably cork-back. For example such material as rubberized or waterproof cloth, mole skin or artificial leather, or fabrikoid.

Still another purpose is to provide an improved reinforcing metal strip provided with slots at its extremities for the reception of rivets adjacent the ends of the slots to secure the anti-wear pieces in position, the slot and the two rivets at each end acting to prevent the anti-wear piece from turning or being misplaced. The slots incidently perform the purpose of exposing a notice of any kind that may be applied to the wear piece, rendering the notice easily discernable.

Still another purpose is to provide an anti-wear piece to receive a single rivet which may have means to prevent the wear piece from turning, and to construct the wear piece in either case wide enough and long enough to prevent misplacement beyond the edges of the reinforcing strip, to insure against wearing or cutting through the flap.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:

Figure 1 is a view in perspective of a school bag showing the application of the anti-wear pieces and the reinforcing strip.

Figure 2 is a view in perspective of a portion of the flap and a portion of the reinforcing strip on an enlarged scale illustrating the anti-wear piece.

Figure 3 is a sectional view on line 3-3 of Figure 2.

Figure 4 is a view in perspective of a portion of the flap, also showing the anti-wear

pieces, but one which is secured by a single rivet.

Figure 5 is a sectional view on line 5—5 of Figure 4, showing the rivet constructed in such wise as to provide means to prevent the anti-wear piece from turning or misplacing.

Figure 6 is a sectional view on line 6—6 of Figure 5 showing the rectangular construction of the shank 8 of the rivet.

10 Referring to the drawings, 1 identifies a school bag, brief case, or the like of an inexpensive type, and which is provided with a cover or over flap 2.

15 A metal reinforcing strip 3 is disposed where the flap folds, that is on the inner surface thereof. This strip 3 is secured adjacent its central portion by upset rivets 4, which also have loops (not shown) to which a handle (not shown) is usually connected. This 20 type of school bag or brief case is very inexpensive, and it is the aim of this invention to distinguish this type of bag from those others which are constructed of genuine leather from the hide.

25 The ends of the reinforcing strip are provided with elongated slots 5, and passing through the slots are rivets 6. Positioned between the ends of the reinforcing strip and flap incident to the fold thereof are anti-wear 30 pieces 7, which may be made of any suitable material preferably genuine leather. These wear pieces are wide enough and long enough to project beyond the edges of the reinforcing strip, hence insuring prevention of wearing or cutting through the flap.

40 The slots are of a width to properly receive the shanks of the rivets, and due to the shanks of the rivets being located at the opposite ends of the slots the anti-wear pieces are prevented from misplacement or turning. The slots further serve the purpose of exposing a notice or legend or any other matter that might be applied to the anti-wear piece.

45 In Figures 4 and 5 the anti-wear pieces are shorter and are also wide enough to project beyond the side and end edges of the reinforcing strip, to insure against wearing or cutting through the flap.

50 However as shown in Figures 4 and 5 the shanks 8 of the rivets are rectangular in cross section, where they pass through the reinforcing strip and through the wear piece, so as to prevent the wear piece from turning. This type of wear piece may be used in very 55 inexpensive school bags and the like. However if necessary the short wear pieces may be long enough to apply a notice or legend thereon, and in such a case the reinforcing strip may have a short slot through which this 60 notice or legend may appear, so as to correspond with what is shown in Figures 1, 2 and 3.

The invention having been set forth, what is claimed is:

65 1. The combination with a bag constructed

of material having relatively slight resistance to wear and having a cover or over flap, of a metal handle securing reinforcing strip secured to the inner face of the flap incident to its fold, an anti-wear piece of considerable thickness between the extremity of each end of the reinforcing strip and the flap, and means passing through the strip, wear piece and the flap for securing the several thicknesses together.

70 2. The combination with a bag constructed of material having relatively slight resistance to wear and having a cover or over flap, of a metal handle securing reinforcing strip secured to the inner face of the flap incident to its fold, an anti-wear piece of considerable thickness between the extremity of each end of the reinforcing strip and the flap, and means passing through the strip, wear piece and the flap for securing the several thicknesses together, each wear piece being wide enough and long enough to protrude beyond the edge of the strip to insure preventing the wearing of the strip through the flap.

75 3. In combination with a bag constructed of material having relatively slight resistance to wear and having a cover or over flap, of a metal handle securing reinforcing strip secured to the inner face of the flap incident to its fold, an anti-wear piece of considerable thickness between the extremity of each end of the reinforcing strip and the flap, and means passing through the strip, wear piece and the flap for securing the several thicknesses together, said reinforcing strip having a slot 80 at one end to allow for shrinkage and adjustment and to expose a notice or legend on the face of the wear piece.

85 4. In combination with a bag constructed of material having relatively slight resistance to wear and having a cover or over flap, of a metal handle securing reinforcing strip secured to the inner face of the flap incident to its fold, an anti-wear piece of considerable thickness between the extremity of each end of the reinforcing strip and the flap, and means passing through the strip, wear piece and the flap for securing the several thicknesses together, said reinforcing strip having a slot 90 at one end to allow for shrinkage and adjustment to expose a notice or legend on the face of the wear piece, each wear piece being wide enough and long enough to protrude beyond the edge of the strip to insure preventing the wearing of the strip through the flap.

95 5. In a school bag constructed of material for relatively slight resistance to wear and having a cover or over flap, the combination 100 with a metal handle securing reinforcing strip disposed adjacent the inner face of the flap incident to the fold thereof, of fibre anti-wear pieces of considerable thickness interposed between the extremities of the strip and the flap,

securing means passing through the strip, wear piece and the flap to secure said thicknesses together, and means cooperating with the securing means to prevent turning of the wear pieces.

⁵ In testimony whereof he affixes his signature.
